UNITED STATES PATENT OFFICE.

JOHN HOLEK AND WILHELM KUCSERIK, OF MILWAUKEE, WISCONSIN.

FISHING-SIGNAL.

1,217,308.

Specification of Letters Patent. Patented Feb. 27, 1917.

Application filed June 24, 1916. Serial No. 105,585.

To all whom it may concern:

Be it known that we, JOHN HOLEK and WILHELM KUCSERIK, a citizen of the United States and a subject of the King of Hungary, respectively, and both residents of Milwaukee, in the county of Milwaukee and State of Wisconsin, have invented certain new and useful Improvements in Fishing-Signals; and we do hereby declare that the following

10 is a full, clear, and exact description thereof.

The present invention relates to new and useful improvements in signal devices, and is more particularly directed to the provision of a signal adapted for use in conjunction with fishing lines, to give both a visible and audible signal upon a fish being hooked.

It is in general the object of the present invention to simplify the structure and 20 prove the efficiency of devices of this character, and to facilitate the readiness with which such devices may be secured in desired positions.

It is a more specific object of the invention 25 to provide such a signal device wherein the audible signal member comprises a spherical bell member of conventional type, and wherein the slot of the bell member coacts with the holding means of the signal, to procure a maximum simplicity of parts.

With the above and other objects and advantages in view the invention resides more particularly in the novel combination, arrangement and formation of parts more particularly hereinafter pointed out and described in the appended claims.

Figure 1 is an elevational view of the improved signal device in set position with the signal member shown in released position in 40 dotted lines.

Fig. 2 is a plan view of the blank from which the head member of the signal is formed.

Referring now more particularly to the 45 accompanying drawings, the improved signal device comprises a head member formed of a single strip of material having one end bent to form a sleeve 6 fixedly receiving one end of an attaching spike 7. The major 50 portion of this strip comprises a finger 8 extending laterally from the spike 7 and the free end of this finger is directed laterally and formed to provide a series of stepped

shoulders 9. Adjacent the sleeve 6 the plate is provided with an extension 10 projecting 55 away from the spike and adapted for the securing thereto of one end of a spring strip 11 by means of lateral flange portions 12 on said projection bent about the strip. Secured to the free end of the strip is a 60 spherical bell member 13 of conventional type provided with the usual slot 14 and the securing of the bell to the strip is at a point diametrically opposite said slot whereby one end of the slot may selectively engage 65 one of the stepped shoulders 9 to thus hold the bell adjacent the finger by reason of the outward resilient pressure of the spring.

For releasing the bell an angular trigger piece 15 is provided which is pivoted at its 70 angle to the intermediate portion of the finger 8 and which has one end adapted to engage the bell to detach it from the finger and which has its other end adapted for securing of a fishing line 16 or other actuating 75 member. Thus upon pulling the line 16, the bell will be released and will spring upwardly to thus give an audible and visible signal.

The attaching spike 7 is relatively long 80 and thin and thus is adapted for ready attachment to any object in the various positions in which it is desired to set the signal member.

Although the signal member has been described as particularly in connection with a fishing line, it is however, apparent that the use of the signal member is by no means limited in this respect and that various uses may be found for the device.

Particularly in connection by use of the device as a fishing signal, however, the adjustable holding means afforded by the series of shoulders 9 is valuable, as in using the device in comparatively rough water, a 95 more secure holding of the signal member against release is desirable than when the device is used in still water.

We claim:

1. A signal device comprising an attaching member, a spring strip connected at one end with the attaching member, a finger connected with the attaching member, a shoulder on the finger and a spherical slotted bell member carried at the other end of the 105 spring strip and having one end of its

slot adapted for abutting engagement with the shoulder.

2. A signal device comprising a plate having one end bent to form a sleeve, an attaching spike fixedly secured in said sleeve, a shoulder at the other end of the plate, a spring strip secured to the plate adjacent said sleeve and means carried by the other

end of the spring strip for abutting engagement with said shoulder.

In testimony that we claim the foregoing we have hereunto set our hands at Milwaukee, in the county of Milwaukee and State of Wisconsin.

JOHN HOLEK.
WILHELM KUCSERIK.
